(57) **CLAIM**

The ornamental design for a grill for automobile, as shown and described.

DESCRIPTION

FIG. 1 is a perspective view from the front of a grill for automobile.

FIG. 2 is a front elevation view thereof.

FIG. 3 is a top plan view thereof; and,

FIG. 4 is a right side elevation view thereof.

The portion of the grille shown in broken lines is for the purpose of showing environmental structure only and forms no part of the claimed design.
